UNITED STATES PATENT OFFICE

JAMES H. GREEN, OF STRATFORD, CONNECTICUT

SAW STRETCHER

Application filed July 10, 1929. Serial No. 377,208.

This invention relates to saws, and more particularly to a saw blade holder and stretcher for saws in which it is desired to readily remove and replace the blade, such as hack saws and butcher saws.

As is well known, it is desirable in hack saws and butcher saws to have the blade readily removable and replaceable, not only because of the ease with which such blades are broken, but also because it is often desirable to use a blade with a different edge for various kinds of work, and further it is often necessary to make such blade and frame easily cleanable for sanitary purposes, and it is an object of this invention to provide a saw blade holder and stretcher which may be readily and easily released and relocked, which will hold the blade firmly and securely under tension and will also hold such blade against twisting in use, thereby reducing its tendency to snap and break and giving better operation as it is always held in proper position.

It is a further object of this invention to provide a blade holder and stretcher which not only permits the blade to be easily removable for cleaning, but which itself may be readily and easily cleaned.

It is an additional object of this invention to provide a blade holder and stretcher which may be used to release and relock the blade without necessity of the use of any tools, which will hold the blade positively, yet may be released and relocked in an instant even by a person of less than average strength.

With the foregoing and other objects in view, the invention consists in certain novel features of construction and arrangement of parts as will be more fully described in connection with the accompanying drawings.

In the drawings

Fig. 1 is a plan view of a saw including an embodiment of this invention.

Fig. 2 is an enlarged plan view of the blade holder and stretcher comprising the invention in closed or locked position.

Fig. 3 is a plan view of the holder and stretcher in released or unlocked position.

Fig. 4 is a sectional view on the line 4—4 of Fig. 2.

Fig. 5 is a sectional view on the line 5—5 of Fig. 2, and

Fig. 6 is a top plan view of the hooked locking lever.

In the drawings 10 represents a saw frame of inverted U-shape and 11 a handle of the type commonly used as hack or butcher saws. A blade 12 is attached thereto at one end 13 in any suitable manner. To the other end of the frame 10 is attached a block 14 having a notch 15 in one end thereof to receive the end of the frame and is secured thereto by a bolt 16. Slidably in a channel 17 in the other end of block 14 is a link 18 having a blade receiving pin 19 at one end thereof. A groove 20 extending partway in the channel permits the pin to enter within the channel, and the channel is of greater width than the thickness of the link 18 by the thickness of a conventional saw blade 12, so that the end of the blade 12 may be placed over pin 19 and then be drawn into channel 17 and the link and the blade will just fill the channel. Hence, the link 18 on one side on the blade 12 and the side of the channel 17 on the other side of the blade cooperate to hold the blade against twisting in use.

When pin 19 has been drawn into the groove 20, the blade is locked in place by the sides of the link and channel, and the means for drawing the pin into the groove comprises a lever 21 pivoted off center to the link as at 22. This lever 21 has a cam surface 23 between pivot 22 and the block ending in a flat 24, so that when the lever is turned on its pivot the cam surface 23 abuts against the block 14 and draws the link 18 through the channel, hence drawing the end of blade 12 into the channel and placing it under tension. To hold the lever in locked position the lever is swung until the flat 24 abuts block 14, whereupon the lever is held in locked position until it is swung in the opposite direction about pivot 22. The other end of lever 21 is formed into a hook 25 of such curvature and length that it will just abut against block 14 when the flat 24 abuts the block, thus protecting the lever against accidental release, as well as facilitating intentional release of the lever.

When it is desired to place a blade in position, the parts are in the position shown in Fig. 3, the blade 12 having just been placed with its end over pin 19 and alongside the link 18. To draw the block into the channel, whereby to hold it firmly under tension and against twisting or turning laterally in use, the lever 21 is turned about the pivot 22. As the lever is turned, the cam 23 abuts 10 against the edge of block 14, drawing the link 18 and blade 12 into channel 17. If necessary, the lever 21 may be placed on a floor, table or other supporting surface, and thus easily turned even by a person of less than 15 average strength, until flat 24 abuts the edge of the block and at the same time the end of hook 25 will also abut the block. The action of flat 24 against the block locks it in place.

20 To release the blade, either to replace it or to clean it, it is only necessary to turn lever 21 in the opposite direction, which may be done by hand or by merely placing hook 25 over a nail on the wall or a butcher hook 25 and drawing the frame 10 downwardly, whereupon the lever will pivot and the blade will be released. It will be noted also, that 30 all the parts of this device are easily cleanable when in released position, and that the blade may be removed and replaced even by a child.

Having thus set forth the nature of my invention, what I claim is:

1. A saw stretcher and holder comprising a substantially U-shaped frame, a handle secured to said frame and so located that one end of the frame projects beyond the handle, a block secured to said projecting end of the frame and adapted to closely fit said end with the forward edge of the latter flush with the face of the block, the upper face of the block flatly abutting the handle so as to afford no crevices between the block, U-frame and handle, a blade secured to the other end of the frame, and means on the block for drawing the blade tight.
2. A saw stretcher and holder comprising a frame, a handle secured to said frame near one of its ends, a block having an L-shaped 50 notch receiving the end portion of the frame and against the end of which the end of the frame abuts with the end of the block abutting the handle and the front edge of the frame flush with the face of the block, a securing means passing through the block and end portion of the frame, and means on the block for anchoring the end of the saw blade.
3. A saw stretcher and holder comprising a block attached to one end of a saw frame, 60 said block having a rectangular shaped channel therethrough, a link in said channel, a pin on said link for the attachment of one end of a saw blade, said channel at one end being of a width and height to snugly but 65 slidably receive the link, said channel at its

other end being of a width and height to snugly receive the link and the end portion of a saw blade on said pin, said channel having a groove in its wall at the end of extra width to snugly accommodate the pin, cam means for drawing the link and pin and end 70 of the saw blade into said channel and securing them there, and said link being so constructed relative to the channel that the pin carrying end of the link is wholly received within the channel and lies flush with the face of the block when the cam means is 75 operated to draw the link into the channel.

In testimony whereof I affix my signature.

JAMES H. GREEN.
